UNITED STATES PATENT OFFICE

2,441,865

PROCESS FOR THE PREPARATION OF ACID
ALKYL SULPHATES

Léonce Bert and Michael Procoffieff, Paris, France,
assignors to Societe Anonyme dite: Societe
D'Innovations Chimiques dite: Sinnova ou
Sadie, Meaux-Beaupré, France

No Drawing. Application July 20, 1945, Serial
No. 606,277. In France November 18, 1943

Section 1, Public Law 690, August 8, 1946
Patent expires November 18, 1963

3 Claims. (CL. 260—459)

1

In a previous French patent application, dated September 28, 1943, entitled, "Process for the obtention of sulphonated aliphatic acids and of their esters," applicant has described a process consisting in subjecting to the action of chlorosulphonic acid, in a neutral solvent, the aliphatic acids of condensation having 6 or more carbon atoms, or their chlorides, anhydrides, amides, nitriles, or esters.

Now, according to the present invention, the surprising discovery has been made that the reaction proceeds in a different manner in regard to the final product, when it is applied to alkyl formates $H-COOR$. Instead of sulphonated alkyl formate $SO_3H-CO-OR$, as expected, acid alkyl sulfate $R-SO_4H$ is obtained.

In a first phase, the alkyl formate is sulphonated by SO_3HCl , as in general, the esters $H-CO_2R$, in accordance with the equation:

The sulphonated formate, which is unstable, then splits into acid alkyl sulphate and carbon monoxide:

so that, finally, the reaction of chlorosulphonic acid with an alkyl formate is expressed by the equation:

and constitutes a new method for producing sulphonated fatty alcohols, with exceptionally high yields.

Another feature of the process according to the invention resides in the fact that sulphonation is effected with heating, whereas, up to the present, it had been generally recommended to sulphonate fatty alcohols without heat.

Example.—1 gram-molecule of alkyl formate (amyl, octyl, lauryl, myristyl, etc. . . . is dis-

solved in ten times its weight of carbon tetrachloride and 1.1 gram-molecule of chlorosulphonic acid is added thereto. The whole is heated with reflux until the discharge of gas ceases and the solvent is then distilled off. The residue of the distillation constitutes the desired crude alkyl sulphate.

Starting with the acid alkyl sulphates thus obtained, these are converted without difficulty into salts and in particular into soluble salts, such as the sodium salt RSO_4Na , the ammonium salt RSO_4NH_4 , sold in the market under the general designation of sulphonated fatty alcohols.

What we claim as our invention and desire to secure by Letters Patent is:

1. A process for the preparation of acid alkyl sulphates consisting in subjecting an alkyl formate having the formula $H-COOR$ wherein R is an alkyl group, to the action of chlorosulphonic acid in a neutral solvent.

2. A process according to claim 1, in which the sulphonation is effected with heating.

3. A process according to claim 1, consisting in dissolving 1 part of said alkyl formate in 10 parts of carbon tetrachloride, adding 1.1 parts of chlorosulphonic acid, heating with reflux until the gaseous discharge ceases, distilling off the solvent and collecting the residue of distillation.
